UNITED STATES PATENT OFFICE.

LEO C. HERMANN, OF EVANSVILLE, INDIANA.

FIRE-STARTER.

No. 884,583.

Specification of Letters Patent. Patented April 14, 1908.

Application filed June 21, 1907. Serial No. 380,169.

To all whom it may concern:

Be it known that I, LEO C. HERMANN, a citizen of the United States, residing at Evansville, in the county of Vanderburg and 5 State of Indiana, have invented certain new and useful improvements in Fire-Starters, of which the following is a specification.

The object of this invention is to provide a device whereby a fire may be started in a 10 range or cooking stove at any time after the coal and kindling have been properly placed, without the presence of a person, the motive power being furnished by a clock, the mechanism of which is similar to that of an alarm 15 clock; a further object being to make the device inexpensive to manufacture and to operate.

For a full description of the invention and the merits thereof and also to acquire a 20 knowledge of the details of construction and the means for effecting the result, reference is to be had to the following description and accompanying drawings.

While the invention may be adapted to 25 different forms and conditions by changes in the structure and minor details without departing from the spirit or essential features thereof, still the preferred embodiment is shown in the accompanying drawings, in 30 which:

Figure 1 is a perspective view showing the invention applied to a cooking stove and adjusted for lighting the fire at the predetermined time. Fig. 2 is a top plan view of the 35 framework supporting the match holder and igniter and the trip mechanism. Fig. 3 is a side view of the complete device, the clock movement being omitted and showing the relation of the parts when set or adjusted for 40 lighting the fire, the dotted lines indicating the raised position of the shaft or spring actuated arm when released. Fig. 4 is a detail perspective view of the outer or rear portion of the supporting frame which receives the clock movement and which is 45 clamped to the stove, the parts being illustrated on a larger scale and showing the clock movement in place. Fig. 5 is a detail perspective view of the outer or rear end of 50 the frame supporting the trip and the match holder and igniter. Fig. 6 is a detail perspective view of the front end portion of the frame illustrated in Figs. 2 and 5. Fig. 7 is a detail perspective view of the match holder. 55 Fig. 8 is a detail perspective view of the means for securing the device to a cross piece

or like part of the stove when the mechanism is adjusted or set for starting the fire. Fig. 9 is a modified form of the rigid portion of the framework clamped to the stove and supporting the clock movement. 60

Corresponding and like parts are referred to in the following description and indicated in all the views of the drawings by the same reference characters.

A is a frame constructed of two wires coiled about the middle, so as to form the eyes A⁵ A⁵, next turning at right angles and running parallel horizontally to the opposite end of the frame. The ends of these wires after being coiled together for some distance, are again separated and are here designated A', 70 A², A³, A⁴. The lower ends A' and A⁴ are coiled forming the eyes A⁶, A⁶ and near the end of the frame form the bends A⁷, A⁷. At 75 the end of the frame said wires are reversed and inclined at a as far as the bends A⁸, A⁸, where they are again reversed, declining, after which they descend vertically to the bend A⁷. The wire A' is coiled around the wire at 80 the bend A⁷, thence running transversely to the opposite side of the frame and there fastened at the bend A⁷. However, a separate piece of wire may be used here, fastened at 85 both ends at the bends A⁷, A⁷, the wire A⁴ also fastening at the bend A⁷ on its respective side of the frame.

The upper wires A² and A³ are coiled forming the eyes A⁹, A⁹. The wire A³ is run through the bend A⁸ and reversed, thence descends vertically, next turned at an angle of 90 degrees and running longitudinally where a little spring A¹⁰ is sleeved thereon, the end of the wire being bent so said spring A¹⁰ cannot slip off. The upper wire A² on the opposite side of the frame A is also run through the bend A⁸ on its respective side of the frame and reversed after it is inclined transversely until over the transverse center of the frame, where it is coiled, forming the eye A¹¹, 100 whence it declines transversely and is fastened around the wire A³ on the opposite side of the frame as shown. The eye A¹¹ affords support for the safety hook F.

The lever C acts as a trip for lever B. 105 Said lever C is constructed of one wire coiled so as to form the eyes C² and C³ and bent on one side so as to form the catch C' and fastened to the lower wire of frame A at the end of said frame. This lever C is operated longitudinally to the plane of the frame A. One end of the wire used in the construction of 110

this lever C extends upward and is bent back at an angle so as to prevent the lever C from being operated forward too far. The upper wire of the frame A prevents it from going 5 too far in the opposite direction.

The wire D runs transversely through the eyes A⁶, A⁶, the lower part being coiled so as to form the eye D². The upper part D' serves as a guide for lever J. The lower end 10 is fastened through the eye A⁶ as shown; the upper end is passed through the same eye and reversed, forming the bend D³. Said bend acts as a stop for the lever J.

The lever B is constructed of one wire bent 15 at B' so as to be placed on the catch C' of lever C and is again bent to form the oblong eye B², thence continuing and turning transversely to the outside of the frame A as shown at B³. The object in forming the oblong eye B² is to add to the weight of that 20 end of the lever. The other end of the wire is coiled and sleeved on the lower part of the transverse wire D, passing through the eye D² and bent to form the hook B⁵. The 25 curved line A¹², represents the edge of the center piece of the stove top behind which the hook B⁵ catches when the device is set, preparatory to operation.

The match striker E is made of sheet iron, 30 the edges of which are crimped so a piece of sand paper can be inserted on which the matches strike. The end E² of said match striker is fastened to the vertical part of the wire A⁴ in a way which allows the opposite 35 end to move horizontally. Said end E² is cut down in width in order to allow the wire E' to cross. The opposite end E³ of said match striker E is guided by the end of the wire A⁸, which passes through same. The 40 spring A¹⁰ sleeved on wire A⁸ bears the match striker E against the match heads when the device is in operation.

The lever J is constructed of one wire forming the coil J' at the end of said lever, 45 said coil is sleeved on the bolt I, which is secured in the eyes A⁵, A⁵. The ends of wire of said lever J are coiled around each other a number of times and separated again, the lower one passing under the transverse wire 50 D' and forming the frame for the match holder J³. The upper wire runs over the transverse wire D' and is bent so as to hold down the matches in the match holder when the device is in operation. The length of 55 said match holder is such as will allow the head end of the matches to protrude one-half inch and high enough to hold from one to three matches. A piece of sheet iron is used in the construction of said match 60 holder which prevents sparks or match stumps from falling out. Said lever J with the match holder J³ is operated transversely by means of a spring H, the coiled part of 65 which is slipped over and held in position by the bolt I. The one end of said spring H is

hooked around the side of the frame A. The other end is hooked around the lever J, thus operating the same, and also holding the wires of said lever J together properly, thus causing them to be guided by the transverse wire D' and the upper wire J⁴ to hold the matches in place. 70

The matches having been properly placed into the holder, the lever J is moved over and secured behind the catch G², which is a part 75 of the lever G, in setting the device preparatory to operation. During this manipulation the match striker E must be held back so that it will not come in contact with the matches, as this would cause them to strike. 80

The trip lever G is operated by a draw bar K, constructed as shown in Figs. 1 and 3. Said lever G is provided with a shoulder G³, to support the draw bar K. The draw bar K is provided on one end with the eyes K' 85 and K². The eye K' is placed over the trip lever G at G³ as shown in Fig. 1 and Fig. 3. The hook F is hooked into the eye K² while setting the device, this is done to prevent accidental tripping or operation. The opposite 90 end of the draw bar K is bent to form the eyes K³ and K⁴. The hook S', which is fastened to the cord S, is hooked into the eye K³. The shaft L shown in Figs. 1 and 3 passes through the eye K⁴. 95

The part which is attached to the edge of the range supports the clock by which the device is operated. It is constructed of a number of different wires. The wire M is bent in the middle, forming the bend M' at 100 the top of the arch. The ends forming the arch descend vertically and are coiled so as to form the eyes M², M². Farther down they are bent at an angle of 90 degrees, running horizontally, the one forming the frame into 105 which the clock is placed, is bent as shown at M⁶, coiled so as to form the eyes M⁶, M⁷, M⁸ and fastened as shown at M⁹; the other end is coiled so as to form the eye M³, next bent at an angle of 90 degrees, ascending vertically 110 and coiled to form the eye M⁴, thence running horizontally and turning at right angles, running transversely, thence descending and forming the eye M⁵, through which the cord S passes, thence inclining and passing through 115 the eye M⁸, where it is coiled around the wire that forms the frame into which the clock is placed, the end of it is turned parallel with said wire, leaving a space between the two wires. The stem of the clock is put into this space. The legs of the clock case are put into the eye M¹ on the one side and into the space between the wires near the eye M⁶ on the other side. In the top of the arch a wire 120 N is placed; the middle of the wire N is bent 125 and placed over the bend in the center of the arch M'. The ends of said wire N run transversely to the plane of the arch passing through the eyes M², M². A spring O is sleeved on the ends of said wire N. The 130

140

shaft L passes over the top of said spring O. The lower ends of said spring O are fastened around the wire of the arch.

The wire P is bent in the middle, forming 5 the eye P³, the ends running transversely and bent as shown, thence reversed at and passing through the eyes M³ and M⁴, thence running parallel with the wire M, at the ends forming the hooks P', P'. These hooks catch 10 around the bottom of the edge of the range or stove top, the wire M being placed upon the top, and are fastened by means of the rings T as shown at T²; to unfasten them the rings are moved away from hooks P'. The 15 brace Q acts as a further support of the construction. It is made of one wire coiled near the end, so as to form the eye Q'. The other end passes through the eye P³, ascending and bent to form the upper part of the eye M⁵ and 20 fastened around the other wire M. At the point Q³ it crosses and is fastened together with the other wire M by means of a small piece of wire. A wire Q⁴ which at the middle is passed through the eye of the brace Q at Q' 25 and at the ends fastened to the hooks P', P', adds to the rigidity of the construction.

The material used in the reel R is wood with an iron-shaft, R² on one end. This shaft R² is journaled in the eye M⁴. To the 30 other end is nailed a wire shaped as shown at R'. The cord S passing through the eye M³ is attached to the middle of the reel R. The end R' of the reel R is attached to the alarm wind of the clock. During the operation the 35 clock winds the cord S on the reel.

The device is operated in the following manner: The coal and kindling having been placed in the stove, a fuse of paper is placed under the kindling with one end. The other 40 end is run up to the top of the range where the device is to be attached as shown in Fig. 1. The matches are then placed into the match holder and lever J with the match holder secured behind the catch G² of lever 45 G. The lever G is thrown forward and the drawbar K is placed on this lever as shown at K', Figs. 1 and 3. The end K³ of the draw bar K passes through the lower eye of lever C. The safety hook F is hooked through the 50 eye K² of drawbar K. The device is then placed on the top of the range as shown in Fig. 1, so the hook B⁵ catches behind the edge of the center piece of the range or stove top. This hook B⁵ keeps the device in the proper 55 position on the stove top, not allowing it to slip out. The lid of the stove top is then placed in its respective place on the one side. The other side of it rests on the inclined wires a and a, as shown in Fig. 1. The end 60 B' of lever B rests upon the catch C' of lever C. The part attached to the edge of the range is next attached as shown in Figs. 1 and 3. The shaft L is passed over the spring O and through the eye K⁴ of the drawbar K, 65 next through the eye C³ of lever C and the

end L² passing through the eye A¹¹ of that part of the device which rests on the top of the range. The other end of the shaft L' slips into the eye M⁵, near where the clock is placed. The hook S' attached to the cord S is hooked into the eye K³ of the draw bar K. The reel R is then attached to the alarm wind of the clock. The safety hook F is now unhooked as shown in Fig. 1. The device is now ready for operation.

The part of the mechanism of the clock which operates the alarm in an ordinary alarm clock is set so it will operate at the desired time, same as an alarm would on an ordinary alarm clock. The clock which is on the ordinary alarm clock type has been altered in some respects. The bell and the tapper have been removed. A little weight has been placed on the wire where tapper has been secured on the inside of the case of the clock. This weight steadies the motion of the mechanism. It requires about twenty seconds for the clock to perform the operation. The clock when in operation, winds up the cord S which is attached by means of the hook S' to draw bar K at the eye K³. The winding up of this cord draws back the drawbar K which first operates the lever G, tripping the match lever J and allowing the matches to strike, which lights the paper or fuse placed on the little wire E'. When the end k at the eye K² comes in contact with the lever C it will trip the lever B. This un-hooks the hook B⁵, allowing the part of the device on the top of the range to slip out and the lid of the range to close as will be readily understood. The drawbar K is slightly bent near the middle so as to cause the end at the eyes K' and K² to swing away from the shaft L during the operation, whereas otherwise it might get caught on said shaft L. The S shaped end of shaft L prevents turning of said shaft and thus keeps the opposite end from coming in contact with the draw bar K. The end E³ of match striker E has a perforation into which one end of the spring A¹⁰ is inserted. This holds said spring A¹⁰ in proper position, preventing friction and facilitating the motion of the match striker E during operation.

In the modification shown in Fig. 9, the arch portion of the supporting frame is constructed so as to dispense with the wire N, the wire M being bent to form the top of the arch M', thence descending and forming the shoulders M⁴ on which the spring O is mounted, the members of the arch descending and being formed substantially as herein indicated. While this style of construction would be a saving in labor and material, it would be more difficult to sleeve the spring O on to its respective place. However, this would be a matter optional with the manufacturer, as one method will answer the purpose as well as the other. The device may

115

120

125

130

be attached to either side of a stove, and when used on a range also the front, but the side which is affected least by the heat is to be preferred. The part of the device which is placed on the top of range or stove is raised and supported a distance above said top by the shaft L. This prevents said part from becoming heated to any extent. The shaft L is operated by the spring O in the arch. 5 It is bent at the end L' and passes through the eye A¹¹ at an angle to facilitate the required motion. The shape of the frame A is such as to cause the lid of the stove top to force said part back when the hook B⁶ is unhooked. The device may also be used on a heater or furnace. When used in this way, the part which is otherwise attached to the edge of the stove must be placed on its side, on a flat surface, (which should be fire proof) 10 in front of the heater or furnace. The part otherwise placed in the top of the stove is placed against the front of the arch and the cord S hooked to the drawbar K. The shaft L and lever B are not used, a fuse being attached in the usual way. The clock need not necessarily be altered, and the alarm may sound during the operation, if desired, or the tapper may be bent so it will not come in contact with the bell. 15 The frame clamped to the stove and supporting the clock movement, constitutes the main or fixed frame. The frame A provided with the match scratch or striker, the match holder and the trip devices constitutes the 20 movable frame. When the mechanism is adjusted for lighting the fire, the parts assume the position indicated most clearly in Fig. 1, that is, the movable frame A is depressed against the tension of the spring O so as to rest upon the stove and is held in the lowered position by the weight of the stove lid or cover 3 and by the hook B⁵ engaging the edge A¹² of the cross piece. The stove lid 25 3 is tilted, the elevated side resting upon the inclined portions a of the movable frame and when the lever B is tripped by the end k of the drawbar coming in contact with the lever C, the hook B is withdrawn from engagement with the cross piece of the stove, there- 30 by permitting the combined force of the spring O and the weight of the stove cover 3 to move the frame A outward or away from the stove opener, so that the cover 3 may drop and close the opening. The movable frame A being released from the weight of the stove cover 3 is lifted by the tension of the spring O so as not to be affected by the heat of the stove. When the hook B⁵ is disengaged from the cross piece of the stove, the 35 stove cover 3 resting upon the inclined portions a, rides thereon and pushes the movable frame outward or away from the stove opening, thereby permitting the cover to descend and close the stove opening and the instant the movable frame clears the stove 40

cover 3, the spring O lifts said frame clear of the stove so as to be out of the way and the direct action of the heat.

The match holder J³, as shown most clearly in Fig. 7, is closed at its rear side by means of 70 a terminal portion of the wire forming the lever J, said closing terminal being indicated at J⁵. This construction prevents rearward displacement of the matches after being properly placed in position and supports the 75 same against the spring tension of the match strike when the appliance is operated. The sides of the match holder are yieldable and grip the matches with sufficient tension to retain them in place. The end J⁴ of the wire 80 closes the top side of the holder which is open.

Having thus described the invention, what is claimed as new is:

1. The combination of a frame comprising 85 relatively vertical and horizontal extensions at opposite sides, a match strike pivoted at one end to the said vertical extension and having its opposite end movable on said horizontal extension and guided thereby, a spring 90 mounted on the horizontal extension of the frame and exerting a pressure against the free end of the match strike, a spring actuated arm provided with a match holder to receive a match and carry the same across the match 95 strike, a catch to hold the said arm in restraint, means to trip the catch and release the arm, and a time controlled mechanism for actuating the said trip means.

2. The combination of a frame comprising 100 relatively vertical and horizontal extensions at opposite sides, a match strike having an eye at one end sleeved upon the said vertical extension at one side of the frame, and having its opposite end slotted to receive the said 105 horizontal extension at the opposite side of the frame, the edges of the match strike being crimped to receive an abrasive strip, a spring sleeved upon the horizontal strip of the frame and exerting a pressure upon the 110 free end of the match strike, a spring actuated arm provided with a match holder to receive a match and carry the same across the match strike, a catch to hold the said arm in restraint, means to trip the catch and release the arm, and a time controlled mechanism 115 for actuating the said trip means.

3. In a fire kindler, the combination of a frame, a match strike, a longitudinal spring actuated match holder, a trip lever parallel 120 ing the match strike and having a stop and a catch, the latter adapted to engage with the match holder and hold it in restraint against its actuating spring, a draw-bar having a portion to engage with said trip lever and 125 supported upon the stop thereof, and a clock movement having connection with said draw-bar to operate the same and effect release of the match holder.

4. In means for lighting a fire, the combi- 130

nation of a frame, a match strike, a spring actuated match holder, a catch for said match holder to hold the same in restraint, a draw-bar, a clock movement for operating said

5 draw-bar at the predetermined time to effect release of the match holder, and a safety hook for preventing premature operation of the aforesaid draw-bar.

5. In means for lighting a fire, the combination of a frame having an inclined portion for supporting a cover of the stove in elevated position, igniting mechanism carried by said frame, engaging means for normally holding said frame in operative position with the 10 inclined portion beneath the stove cover, a trip for the igniting and engaging devices, and a clock movement for actuating said trip.

6. In means for starting a fire, the combination of a frame having an inclined portion 20 to engage with and hold a stove cover in elevated position, igniting means mounted upon said frame, engaging means carried by the frame to normally hold it in operative position when set for lighting the fire, means for 25 tripping the igniting means, whereby the fire is lighted, means for tripping the said engaging means to permit the frame to move out of the way after the fire has been started so that the stove cover may close, and a clock movement 30 for actuating the aforesaid trip means.

7. In a fire starter, the combination of a frame having a portion to come beneath a stove cover and hold the same elevated, igniting means mounted upon said frame, 35 a lever having a hook to engage with a portion of the stove to hold the frame in operative position when adjusted to hold the stove cover in elevated position, catches for the said igniting means and the hooked lever, 40 means for tripping the igniting means and the said hooked lever in successive order, whereby the fire is lighted and a moment later the frame released to permit closing of the stove cover, and a clock movement for actuating 45 the said trip means.

8. In means for starting a fire, the combination of a frame having a portion to extend beneath a stove cover and hold the same elevated, igniting means mounted upon 50 said frame, a catch for holding the igniting means in restraint, a pivoted lever mounted upon the frame and having a hooked end to engage with a portion of the stove and hold the frame in operative position, a catch for 55 holding said hooked lever in given position, a draw-bar having a portion to engage with the said catches and trip the same in suc-

sive order, and a clock movement for operating the draw-bar at the predetermined time.

60

9. In a fire starter, the combination of a movable frame provided with igniting means, a main frame adapted to be secured to the stove, a spring actuated shaft attached to the main frame and supporting the movable frame, a clock movement mounted upon the main frame, and connecting means between the clock movement and trip devices of the movable frame to effect release of the latter and the igniting means.

70

10. In a fire starter, the combination of a movable frame provided with igniting means and a trip device, a main frame adapted to be clamped to the stove, a spring actuated support for the movable frame attached to and carried by the main frame, a clock movement mounted upon said main frame, and connecting means between the clock movement and the trip device of the movable frame to effect release of the igniting means and 80 said movable frame, whereby the spring actuated support may come into play and lift said movable frame from the stove.

75

11. In a fire starter, the combination of a main frame comprising clamp members, 85 means coöperating with said clamp members to cause them to grip a portion of the stove, a clock movement fitted to the outer end of said main frame, an upright portion at the inner end of said main frame, a spring actuated support mounted upon said main frame, a movable frame mounted upon said spring actuated support and having a portion adapted to extend beneath and hold a stove cover in elevated position, engaging means 90 carried by the movable frame to hold it in operative position, a catch for said engaging means, igniting means mounted upon the movable frame, a catch for said igniting means to normally hold it in restraint, 100 and connecting means between the clock movement and the said catches to effect release of the igniting means and the said engaging means in successive order at the predetermined time, whereby the fire is first 105 started and the movable frame subsequently automatically released and moved away from the stove.

95

In testimony whereof I affix my signature in presence of two witnesses.
